ELECTRIC RELAY

Filed Aug. 29, 1921

Inventor

HENRI CHIREIX

By his Attorney *Frank Adams*

UNITED STATES PATENT OFFICE.

HENRI CHIREIX, OF PARIS, FRANCE.

ELECTRIC RELAY.

Application filed August 29, 1921. Serial No. 496,668.

To all whom it may concern:

Be it known that I, HENRI CHIREIX, a citizen of France, and a resident of Paris, France, have invented certain new and useful Improvements in Electric Relays, of which the following is a specification accompanied by drawings.

The object of the present addition is to provide for certain modifications of the ultra-sensitive relay system described in the application filed Aug. 29, 1921, Serial No. 496,667. More particularly, it relates to the arrangement of the controlling element and the starting arrangement of the annunciator apparatus for preventing the untimely operation of this apparatus.

In order to vary the resistance of the circuit, a three-electrode tube is used in accordance with the statement contained in the last paragraph of said application. In accordance with the present invention, the tube has the form of a detector, e. g., by inserting a shunted capacity in the grid circuit of this tube. On the other hand, the actuation of the annunciator (e. g., a bell) is accomplished by means of a thermostat, or other analogous apparatus, the energization of which is combined with that of the relay in the working period, whereby a cumulative effect is obtained under the control of the calling signals or the weak current to be detected. This effect cannot be produced by atmospherics of even the strongest character.

The invention will be more clearly understood from the single figure of the drawing which diagrammatically represents, for the purpose of illustration and not limitation, an apparatus constructed in accordance with the above.

The elements of which the arrangement of the preceding application is composed, will be found also in this figure: The oscillation generator tube 1 comprises a plate circuit including two resonant circuits 2 and 3 tuned to different frequencies without direct mutual reaction. Preferably, these circuits are coupled with the grid circuit, through the mutual induction of coils 5 and 7 to the coils 4 and 6 respectively. The oscillating circuits 2 and 3 are respectively completed by variable condensers 8 and 9. Furthermore, the oscillating circuit 3 includes an intensity indicator 11 (milliamme-

ter, relay, etc.), the circuit connections and functions of which will be hereinafter set forth. On the other hand, the absorption circuit discussed in the application referred to above, comprises the three-electrode tube 12, the plate circuit of which is coupled through coil 13 with the oscillating circuit 2. The resistance of the space between the plate and the filament of this tube is subjected to variations under the control of the weak current (or signal waves) to be detected. The effect of this current (or signal) manifests itself on the grid of tube 12 through the agency of transformer 16.

The tube 12 is mounted as a detector by means of any one of the well known circuits, such as the one shown in the drawing; in which in its grid circuit a condenser 17 is shunted by a high resistance or grid leak 18. The important advantages resulting from this new arrangement of tube 12 consist in that it is possible to operate the system with very weak currents.

The current indicator 11 operates a contact 19 which closes the circuit containing a battery 20 and a relay 21 of any well known type. This relay has a double function: On one hand, by closing contacts 22 it causes the operation of the signaling or indicating element (bell, visual signal, stylus, etc.) which is illustrated in the present case in the form of a bell 23; and on the other hand, by closing a short circuiting contact 24 of the condenser of circuit 9, it restores the generator 1 to its normal oscillating condition. Preferably, the operation of the signaling element 23 under the control of contact 22, is arranged by the interposition of a device belonging to the class of the energy integrators (thermic systems with mechanical or electrical oscillations, etc.). In the present embodiment, this element is represented by a thermostat comprising a contact thermometer 25 heated by a resistance 26.

The handling and the operation of the sensitive relay system, arranged in accordance with the present invention as above described, or in an analogous manner, may be explained in the following manner, the different adjustments being stated in detail:

The circuits 2 and 3 are tuned in such a manner that the maintenance of the oscillations may be equally well effected either to

the neighboring frequency of the oscillations of circuit 2, or to the neighboring frequency of the oscillations of circuit 3. For the sake of brevity, these oscillation conditions will be referred to as condition II which is waiting or idle condition, and condition III which is the operating condition. It should be noted, however, that the negative resistance of circuit 2 preferably should have a slightly higher absolute value than that of circuit 3 for which the condition of maintenance is just satisfactory. The result of these tunings (which constitutes at the same time their practical verification) will be felt in that when the controlling circuit 12, 13 is not operating upon starting of the oscillation of the system (at the time the tubes are started, or as a result of any other cause) it will be in condition II. A weak current (signal, etc.) traversing the primary winding of transformer 16 varies in the well known manner the plate-filament current of tube 12 which forms part of the absorption circuit 12, 13. A modification of the apparent electrical constants of circuit 2 results from this (more specifically, the apparent ohmic resistance of the circuit is increased); condition II ceases and condition III is established. When the resistance of the controlling circuit 12, 13 resumes its normal value, i. e. upon the cessation of the signal, the system does not resume the original oscillating condition (condition II). This result, however, could be obtained in certain special cases by means of very precise and delicate tuning of the circuits. In the present embodiment of the invention, the two oscillating conditions being possible, when once started, the condition III remains established. In order to return to the condition II or starting condition, operations must be performed to eliminate condition III. These operations may be of varying nature. For example, in the copending application referred to above, circuit III is grounded. The ground connection may be established by means of a manually actuated contact (press button, etc.). In accordance with this modification, this operation may also be performed, by actuating a contact 24 to short circuit the oscillating circuit 3, for example, by short circuiting condenser 9. It should be noted at this point that, normally, it is the beginning of the signal that increases the resistance of the controlling circuit 12, 13 and thus starts the system. Nevertheless, if the signal is too weak, the resistance is not sufficiently unstable to render unstable the condition II.

This resistance variation reduces only slightly the absolute value of the negative resistance of circuit 2 and would render it inferior to that of circuit 3. But on account of the phenomenon that the pre-existing os-

cillation persists, this is insufficient to start condition III upon the cessation of condition II.

Due to this, upon the arrival of a weak signal the system will not be actuated.

Experience shows, that in the circuit arrangements described in this modification, however, the disappearance of the weak signal starts the system into operation, notwithstanding the fact that the arrival of this signal did not have this effect. This seems to be due to the disturbances caused by the cessation of the signal, i. e., to the sudden discharge of the shunted condenser 9. The beginning of the signal does not cause the cessation of condition II, but the negative resistance corresponding thereto becomes smaller than that corresponding to condition III. It is sufficient, therefore, if the disturbance due to the very rapid discharge of the shunted condenser upon the cessation of the signal causes the instantaneous passage from the less stable condition II to the more stable condition III.

The discharge of the condenser continues, the resistance resumes its initial value but, as above stated, the condition III which has just been brought about, maintains itself and persists until it is destroyed by the above mentioned operation. It will be seen that, the effect of the shunted capacity provided in the grid circuit (or that of any equivalent arrangement) is to make possible the starting of the apparatus even if the currents are weaker than those adapted to actuate an apparatus such as the one described in the copending application.

During condition III, the indicating apparatus 2 is actuated, and in the present case, it actuates in turn the sensitive relay 21. This sensitive relay 21 closes, on one hand, a circuit in shunt to the local battery 20, and on the other hand, by actuating contact 24, it short circuits the circuit 3, whereby condition II or the waiting condition is reestablished. The timing of contact 22, the lapse of time between the closure of contact 22 and contact 24, and the frequency of the impulses of relay 21 may obviously be subject to arbitrary regulation depending on the object to be attained. The operation of indicator 11 in response to the closure of these contacts (sensitive relay 21) may be varied without departing from the spirit of the present invention. Under the control of a signal, a series of current impulses will be received in the local resistance 26. This will heat the thermostat and after the lapse of a certain period of time, the latter will close the contact of the annunciator 23, if during this time the contact 22 has been closed a sufficient number of times. The character of the signaling impulses (or of the weak current) actuating 16, may be deduced from the operating conditions. If this current is

sufficiently strong to cause at the beginning of its action the starting of the conditions, it is of no consequence whether it is continuous or interrupted. On the other hand, if 5 this current is very weak and brings about the conditions only upon its cessation, it is an interrupted (or alternating) current and of such frequency that the desired number 10 of interruptions will be obtained at 22 depending on the adjustment and the constants of the thermostat.

In the above described system if an energy integrator of the pendular type is used in the place of a thermostat, it may be advisable 15 to establish a resonance (mechanical or electrical or electrical and mechanical) between the oscillations of this system and those of the signaling current. The sensitive relay 21, in suitably modified form, may be 20 syntonized. In this manner, concurrently with the action of the thermostat, or otherwise, the annunciator 23 is actuated and not even intense disturbances could produce this 25 result, because they are neither of sufficient duration, nor have they the necessary characteristics.

The above described invention, however, is independent of the above stated hypothesis given in explaining the operation.

30 Without departing from the spirit of the invention, provisions may be made for numerous modifications of the arrangements herein disclosed, or different arrangements may be designed in accordance with the 35 principle of the present invention.

Having described my invention what I claim is:

1. A relay for electric currents comprising an oscillation generator having two oscillating circuits connected thereto tuned to different frequencies, means associated with 40 said generator for causing it to oscillate at either of said frequencies separately and a vacuum tube subjected to said currents having a circuit associated with one of said oscillating circuits.

2. A relay for electric currents comprising an oscillation generator having two oscillating circuits connected thereto tuned to different frequencies, means associated with 45 said generator for causing it to oscillate at either of said frequencies separately and a vacuum tube having an input circuit subjected to said currents and an output circuit associated with one of said oscillating circuits.

3. A relay for electric currents comprising an oscillation generator having two oscillating circuits connected thereto tuned to different frequencies, a vacuum tube subjected to said currents and having a circuit associated with one of said oscillatory circuits and integrating means associated with 50 one of said oscillating circuits.

4. A relay for electric currents comprising 65 an oscillation generator having two oscillating circuits connected thereto tuned to different frequencies, a vacuum tube having a circuit subjected to said currents and an output circuit associated with one of said oscillating circuits, current integrating means cooperating with one of said oscillating circuits and indicating means cooperating with said integrating means.

5. A relay for electric currents comprising 70 an oscillation generator having two oscillating circuits connected thereto tuned to different frequencies, a vacuum tube subjected to said currents and having a circuit cooperating with one of said oscillatory circuits, a tuned relay cooperating with said last mentioned oscillatory circuit and integrating means cooperating with said tuned relay.

6. A relay for electric currents comprising 75 an oscillation generator having two oscillating circuits connected thereto tuned to different frequencies, means associated with said generator for causing it to oscillate at either of said frequencies separately and a three electrode vacuum tube having a grid circuit coupled to the source of said currents and a plate circuit coupled to one of said oscillating circuits.

7. A relay for electric currents comprising 80 an oscillation generator having two oscillating circuits connected thereto tuned to different frequencies, means associated with said generator for causing it to oscillate at either of said frequencies separately a three 85 electrode vacuum tube having a grid circuit coupled to the source of said currents and a plate circuit coupled to one of said oscillating circuits, and a relay cooperating with the other oscillating circuit.

8. A relay for electric currents comprising 90 an oscillation generator having two oscillating circuits connected thereto tuned to different frequencies, a three electrode vacuum tube having a grid circuit coupled to the source of said currents and a plate circuit coupled to one of said oscillating circuits, a relay cooperating with the other oscillating circuit and means actuated by said 95 relay for short circuiting said last mentioned oscillating circuit.

9. A relay for electric currents comprising 100 an oscillation generator having two oscillating circuits connected thereto tuned to different frequencies, a three-electrode vacuum tube having a grid circuit coupled to the source of said currents and a plate circuit coupled to one of said oscillating circuits, a relay cooperating with the other oscillatory circuit and current integrating means, cooperatively associated with said 105 relay.

10. A relay for electric currents comprising 110

- ing an oscillation generator having two oscillating circuits connected thereto tuned to different frequencies, a three-electrode vacuum tube having a grid circuit coupled to the source of said currents and a plate circuit coupled to one of said oscillating circuits, a relay cooperating with the other oscillatory circuit, means actuated by said relay for short circuiting said last mentioned oscillatory circuit and current integrating means cooperatively associated with said relay.
11. A relay for electric currents comprising a three-electrode oscillation generator having two oscillating circuits connected in the plate circuit, a second three electrode valve having its grid circuit coupled to the source of said currents, a condenser in the grid circuit, a plate circuit coupled to one of said oscillating circuits, a relay having a coil cooperating with the other oscillating circuit, means actuated by said relay for short circuiting said last mentioned oscillatory circuit, a current integrator actuated by said relay and indicating means cooperating with said integrator.
12. A relay for electric currents comprising an oscillation generator having two oscillating circuits connected thereto, tuned to different frequencies, said generator being constructed and arranged to oscillate normally at one only of said frequencies and under predetermined conditions to oscillate at the other only, and means comprising a vacuum tube subjected to said currents for varying the constants of one of said circuits to cause a change in the oscillation frequency of said generator.
13. A relay for electric currents comprising an oscillation generator having two oscillating circuits connected thereto, tuned to different frequencies, said generator being constructed and arranged to oscillate normally at one only of said frequencies and under predetermined conditions to oscillate at the other only, and means comprising a vacuum tube having an input circuit subjected to said currents and an output circuit associated with one of said oscillating circuits to cause a change in the oscillation frequency of said generator.
14. A relay for electric currents comprising an oscillation generator having two oscillating circuits connected thereto, tuned to different frequencies, said generator being constructed and arranged to oscillate normally at one only of said frequencies and under predetermined conditions to oscillate at the other only, means comprising a vacuum tube subjected to said currents for varying the constants of one of said circuits to cause a change in the oscillation frequency of said generator, and integrating means associated with one of said oscillating circuits.
15. A relay for electric currents comprising an oscillation generator having two oscillating circuits connected thereto, tuned to different frequencies, said generator being constructed and arranged to oscillate normally at one only of said frequencies and under predetermined conditions to oscillate at the other only, means comprising a vacuum tube subjected to said currents for varying the constants of one of said circuits to cause a change in the oscillation frequency of said generator, and a tuned relay cooperating with one of said oscillatory circuits and integrating means cooperating with said tuned relay.
16. A relay for electric currents comprising an oscillation generator having two oscillating circuits connected thereto, tuned to different frequencies, said generator being constructed and arranged to oscillate normally at one only of said frequencies and under predetermined conditions to oscillate at the other only, means comprising a vacuum tube subjected to said currents for varying the constants of said circuits to cause a change in the oscillation frequency of said generator, and means comprising a three-electrode vacuum tube having its grid circuit coupled to the source of said currents and its plate circuit coupled to one of said oscillating circuits.

HENRI CHIREIX.
